Primary Examiner—Terry A. Wallace*Attorney, Agent, or Firm*—Richard B. O'Planick; Lisa B. Riedesel[57] **CLAIM**

The ornamental design for a lid for a food storage container, as shown and described.

DESCRIPTION

FIG. 1 is a top right front perspective view of a lid for a food storage container showing my new design;

FIG. 2 is a top plan view thereof;

FIG. 3 is a bottom plan view thereof;

FIG. 4 is a right side elevational view thereof; the rear elevational view being a mirror image;

FIG. 5 is a front elevational view thereof; the left side elevational view being a mirror image;

FIG. 6 is a top, right, front perspective view of an alternate embodiment of FIG. 1;

FIG. 7 is a top plan view of FIG. 6;

FIG. 8 is a front elevational view of FIG. 6, the rear elevational view being a mirror image;

FIG. 9 is a bottom plan view of FIG. 6;

FIG. 10 is a left side elevational view of FIG. 6; and,

FIG. 11 is a right side elevational view of FIG. 6.

FIG. 1

FIG. 2

FIG. 3

FIG. 4

FIG. 5

FIG. 6

FIG. 7

FIG. 8

FIG. 9

FIG. 10

FIG. 11
